UNITED STATES PATENT OFFICE

FRANCIS BETTS SMITH, OF SAN FRANCISCO, CALIFORNIA

METHOD OF AND APPARATUS FOR SETTING PRECAST FORMS IN AQUEOUS BODIES

Application filed October 27, 1928. Serial No. 315,417.

The present invention relates to a method of and an apparatus for setting on a mud, or other soft bottom, tubes or bodies which are assembled or pre-cast, moved to position, and thereafter submerged in an aqueous body.

The invention has for its principal object to provide a supporting method for assembled or pre-cast bodies, which will enable the body to be temporarily set on a mud bottom and immediately thereafter be cheaply, quickly, and easily permanently set on supports or foundations which will preclude the settling thereof, and which will afford adequate, permanent foundation, even if the supporting area be mud, or other soft structure.

Another object is to provide a form associated with the assembled or pre-cast body in such manner that when positioning the assembled or pre-cast body, the form is movable therewith and may be lowered over the ends of projecting piling or supports and thereafter filled with a binding medium, which forms a cradle for the assembled or pre-cast body, and which will engage the piling and form therewith a directly supporting mass.

The invention consists broadly in a plurality of open forms attached to the assembled or pre-cast body, and submergeable therewith, for cooperation with an artificial foundation during the leveling and aligning of the body, and which are so constructed as to permit the filling thereof with concrete, or other composite mass, which will harden and form a support for the assembled or pre-cast body, the mass uniting with the artificial foundation.

With the above mentioned and other objects in view, the invention consists in the novel construction and combination of parts hereinafter described, illustrated in the accompanying drawings, and pointed out in the claims hereto appended; it being understood that various changes in the form, proportion, size and minor details of construction within the scope of the claims may be resorted to without departing from the spirit or sacrificing any of the advantages of the invention.

In the drawings, disclosing the preferred embodiment of the invention—

Fig. 1 is a view in side elevation of an assembled or pre-cast body submerged in an aqueous body and supported at a desired grade.

Fig. 2 is a vertical sectional view on line 2—2 of Fig. 1 disclosing the means for aligning and leveling the assembled or pre-cast structure.

Fig. 3 is a section on line 3—3 of Fig. 1, illustrating one of the steel forms positioned over the projecting ends of the piles driven into the mud bottom.

Referring to the several views of the drawings, wherein like characters designate corresponding parts, 1 indicates an assembled or pre-cast form, in the present invention it being in the form of a cylindrical tube of sufficient size to afford a vehicular tunnel, or passageway, lying beneath the surface of a body of water. While but one segment of the tubular type is shown, it is to be understood that any number may be employed, they being arranged in end to end alignment to form a continuous tube or tunnel beneath the surface of the aqueous body. Also the assembled or pre-cast body may be composed of a double barrelled structure, such that two tubular structures are provided, as the assembled or pre-cast bodies are arranged in end to end alignment beneath the surface of the aqueous body.

The interior of the tubular assembled or pre-cast body is provided with a longitudinal extending transversely disposed dividing wall 2, forming a ballast chamber 3 longitudinally of the body. Within said chamber 3 is adapted to be received ballast fluid, such as water, for the purpose hereinafter described.

On the surface of the wall 2 is deposited a body of sand, or other ballast, the surface of which or of the wall 2 forms the roadway or walkway longitudinally of the assembled or pre-cast body.

Adjacent its ends, the outer surface of the body 1, beneath the wall 2 and ballast chamber 3, is formed with an outwardly extending bracket 4, the undersurface of which is

preferably disposed in parallel relation with the surface of the wall 2.

Cooperating with the lower edge of each bracket 4 is an anchor block 5 suspended beneath its associated bracket 4 by suitable hangers 6 extending through the bracket into the interior of the tubular portion of the assembled or pre-cast body. The hangers are illustrated as being united by a common connector 7, which is operated by any suitable means to move through the hangers 6, anchor block 5, to and from the undersurface of the bracket 4.

At points desired, there are secured to the surface of the assembled or pre-cast body 1, suitable hollow forms 8, preferably of metallic structure, they being open along their bottom edge 9; closed along their edges 10; and open at their upper ends on each side of the assembled or pre-cast body, as at 11.

These forms are arranged with their bottom edge extending parallel with and beneath the wall 2, and in elevation the forms are of an outline simulating a pipe supporting cradle.

In the embodiment illustrated, the forms 8 are attached to the surface of the assembled or pre-cast body 1 by means of bolts, or other connections, not shown.

With the member 1 formed in any suitable manner, with the brackets 4 integral therewith, and the forms 8 attached thereto, and with ballast in chamber 3 and on the wall 2, and with the ends of the body closed by suitable bulk-heads, the body is floated or launched in a stream, or suitable body of water, in which it floats partly submerged.

With the bed of the stream, or aqueous body, which is to receive the pre-cast body, 40 suitably smoothed or dredged, has driven thereinto lines or groups 13 of piling located to correspond with the spacing of the forms 8 on the body 1, the ends of the piling adapted to project above the surface of the bed of the aqueous body.

The assembled or pre-cast body 1 is brought to the desired location for submerging and by the addition thereto of additional ballast the member or tube is caused to gradually sub- 50 merge.

By control of the quantity of ballast added to the member or tube its buoyancy is regulated to such a fineness that when the body approaches the bottom, the anchor blocks 5 rest lightly upon the temporary base 14, the forms 8 overlying the piles 13.

By the operation of mechanism not illustrated, and forming no part of this invention, the anchor blocks 5, through hangers 6, are 60 operated to adjust the tube to the desired grade. Immediately thereafter, concrete, or other materials capable of setting and forming a support or cradle base, is poured into each form 8, through its openings 11. After 65 this is set, the tube is bedded, or back-filled, in

any of the well known manners, permitting the weight of the tube and back-fill to rest on the newly formed cradles within forms 8.

While the formation and bedding of but one single tubular section is described, and the preferred method set forth in detail, it is to be understood that any number of single or twin tubular sections are adapted for formation and bedding in the same manner, the bedding taking place in end to end relation, and when the abutting joints are sealed and the bulk-heads removed, a continuous tube, tunnel, or passage for any desired purpose is provided.

I claim:—

1. The method of setting submersible structures containing buoyancy means and carrying spaced hollow foundation forms in aqueous bodies which consists in preparing the bottom of the aqueous body by driving piles thereinto, arranged in groups, with the ends of the piles projecting above the bottom of the aqueous body, the groups being spaced corresponding to the distance between the hollow foundation forms, operating the buoyancy means to cause the gradual submergence of the structure to its desired position with each hollow foundation form receiving through its bottom the projecting ends of one of the groups of piles, then filling the foundation forms with concrete to form therein foundations in which the projecting ends of said piles are embedded.

2. A structure for submergence in an aqueous body, comprising a body having a chamber affording a buoyancy means, and a plurality of foundation forms carried at spaced points in longitudinal alignment on the exterior of the body, said forms being hollow, having an open bottom and provided with a filling opening near their top.

3. A structure for submergence in an aqueous body, comprising an elongated tubular body provided on its interior with a transversely disposed, longitudinally extending way wall and on its outside with a bracket, the wall surface of which is parallel with the surface of the way wall, a plurality of hangers of rigid structure adjustably extending through the body wall and bracket, and an anchor block suspended beneath the bracket by said hangers and movable to and from the bracket on the adjustment of said hangers.

In testimony whereof I have signed my name to this specification.

FRANCIS BETTS SMITH.
